UNITED STATES PATENT OFFICE.

SAMUEL A. JACOBS, OF BROOKLYN, NEW YORK, ASSIGNOR TO MERGENTHALER LINOTYPE COMPANY, A CORPORATION OF NEW YORK.

TYPOGRAPHICAL ELEMENT.

1,382,088.

Specification of Letters Patent. Patented June 21, 1921.

Application filed December 11, 1919. Serial No. 344,190.

To all whom it may concern:

Be it known that I, SAMUEL A. JACOBS, a subject of the Shah of Persia, residing at Brooklyn, in the county of Kings and State 5 of New York, have invented certain new and useful Improvements in Typographical Elements, of which the following is a specification, reference being had therein to the accompanying drawing.

10 This invention relates to typographical elements, such as those employed in the commercial linotype machines for the production of printing slugs, and contemplates improvements which will enable these machines 15 to be used more readily in connection with Syriac and like languages. As is well known, printing in these languages has heretofore required more than four hundred different type characters to a font, which number is 20 entirely too large for the practical composition of matter on the regular linotype machines.

The object of the present invention is to reduce the number of these characters and 25 to such extent that the existing linotype machines may be adapted to the requirements of the language. The manner in which this result is attained will be fully set forth in the detailed description to follow.

30 Referring to the drawings:

Figure 1 shows a set of simple characters of the Syriac alphabet;

Fig. 2 shows variations of such characters;

35 Fig. 3 shows a group of additional characters which are made of special form in accordance with this invention;

Fig. 4 shows compound characters made up by combinations of characters of Figs. 1 and 3;

40 Fig. 5 shows a character in simple form joined to a compound accented character;

Fig. 6 is a perspective view of two-type producing matrices, the elements used in the commercial linotype machine;

45 Fig. 7 is a similar view showing such matrices assembled side by side and in the relative position they occupy during the casting operation.

The Syriac alphabet comprises twenty-two 50 characters (not considering the different forms), of which fourteen are designed to connect both at the left and right and the

remaining eight at the right only. The present invention deals only with the fourteen characters connecting at the left and right, 55 which characters are illustrated in Fig. 1 and designated 1 to 14, being in the simplest form of the Nestorian style. The variations of such characters are indicated in Fig. 2, wherein those numbered 15 to 18 are the as- 60pirated characters; those numbered 19 to 22 are the respiration characters; and those numbered 23 to 25 are the ones susceptible to foreign sounds. The foregoing characters (which will be termed primary characters) are formed for common alinement so as to connect with one another and with the additional characters (which will be termed appendage characters) now to be described.

Such appendage characters are illustrated 70 in Fig. 3, wherein they are designated 26, 27, 28 and 29 respectively, each made up of two distinct parts *a* and *a'*. The parts *a* are the four principal forms of accents or vowel signs employed in the Syriac language, and 75 the common part *a'* is what will be termed a primary-character-extension. In this connection, it may be noted that the large number of characters heretofore required has been due chiefly to these particular accents, 80 which are used with all of the alphabet characters in all of their variations.

The primary characters 1 to 25 are complete in themselves and may be used alone for printing in the usual way. The appendage characters 26 to 29, on the other hand, are meaningless in themselves and cannot be used alone but are intended to be joined to the primary characters to produce other characters of distinct form or having a different significance. Thus, when one of the appendage characters is joined to one of the primary characters, the effect is to produce a compound accented character, which of course has an entirely different significance 95 from that of an unaccented character as represented by a primary character alone. It is pointed out that any one of the appendage characters may be so joined to any one of the primary characters, so that by the use of 100 but twenty-nine characters, there may be produced as many as one hundred twenty-nine different printed letters, representing a saving of one hundred characters.

In Fig. 4, there are shown compound accented characters 30, 31, 32 and 33, produced respectively by the juncture of the appendage characters 26, 27, 28 and 29 and primary characters 1, 2, 3 and 4, although of course any other pair of such characters could be joined in the same way. It will be noted that the part a' of each appendage character extends the primary character somewhat to the left, and that consequently the associated accent a comes above a portion of the complete compound character as required. Each appendage character, then, is made to perform two distinct functions, to wit, it not only adds the appropriate accent to the primary character, but it extends such character to the left or in the direction of reading or writing, with the result that the compound character appears in print as a complete accented letter of usual form, although it is made up from absolutely distinct characters. It will now be apparent that letters as thus produced answer all the orthographic and grammatical requirements of the Syriac language, in that the accent is located above or below the whole letter. However, in order that the accents may appear in print in more symmetrical relation to the body of the letter and to identify them positively therewith, those which occur above the letter, namely, the accents of appendage characters 26 and 28, are inclined toward the right as shown, so that no possible confusion can arise however close the letters may be arranged in print.

In addition to the important function just described, the common part a' of the appendage characters also acts as a ligature to connect a preceding character with a following character. Thus, in Fig. 5, the appendage character 26 occurs between two primary characters 1 and 4, and it will be noted that the appendage character has not only converted the primary character 1 from its simplest form into one of the accented variety, but also that it has provided a connection between such accented character and the following primary character 4 which is in its simplest form, although, of course, it could be in any other form. In this connection, it may be observed that in these languages all of the characters which are intended to be connected to succeeding characters are formed at their left with "connection bars" so that the letters in print will be joined together as a whole in the manner illustrated. Hence, the use of the part a' is well adapted to carry out this further requirement of the language, the only effect being to extend the character to which it is joined somewhat to the left, which is perfectly proper and acceptable. It is because the eight alphabet characters not here-

in illustrated do not connect to the left, and hence cannot be extended in that direction, that they are not used in connection with the present improvements. It should perhaps also be made clear that there are other accents besides the four principal ones above mentioned that appear in the Syriac language. These other accents, however, are confined in their use to certain of the alphabet characters, usually to one only, and hence can not be employed universally as in the case of the four principal forms.

For the sake of clearness, in the foregoing description and in the figures of the drawings to which reference is made, only the characters as they appear in print have been dealt with, but it will have been understood that in use the characters will be carried by typographical bodies or elements such as before referred to. As the present invention has been developed with the requirements of the linotype machine in mind, the element herein illustrated by way of example is the regular form of matrix employed in such machine. Two such matrices are shown in Fig. 6, each consisting of a flat body portion A provided at its opposite edges with projecting ears A^1 and at the top with distributing teeth A^2 whereby it is adapted to be circulated through the linotype machine in the regular way. In its mold engaging edge, each matrix is formed with a notch or routing A^3 containing at its bottom a depression or cavity A^4 constituting the character of the matrix. In this instance, then, the character is of intaglio form, consisting of a depression or cavity wherein is cast the type character from which the print is to be made. In the operation of the linotype machine, these matrices are first assembled side by side in line and then presented as a whole to a slotted mold for the casting of an integral bar or slug bearing on one edge the complete line of type characters formed in the cavities A^4 of the matrices, all as well understood in the art. One of the matrices shown in Fig. 6 (which will be regarded as a main element) has its cavity A^4 formed to correspond with the primary character 1, whereas the other matrix (which will be regarded as an auxiliary element) has its cavity formed to correspond with the appendage character 26, it being understood that a set of main elements will be provided for all of the twenty-five primary characters, and a further group of auxiliary elements for the four appendage characters. In Fig. 7, the two matrices are shown assembled side by side in the relative position they occupy during the casting operation, and it will be noted that the portion of the cavity of the auxiliary matrix corresponding to the part a' of the appendage character 26 communicates laterally with the portion of the cavity

of the main matrix corresponding to the "connection bar" of the primary character 1. The slug cast from such matrices will therefore present at one portion in its 5 length a single integral type character from which will be printed the compound accented letter 30 shown in Fig. 4.

Generally speaking therefore, the present 10 invention provides, in a typographical font, a set of main elements formed with primary characters, and an auxiliary element formed with an appendage character consisting of a primary-character-extension and an accent associated therewith, the said auxiliary element 15 adapted to be used conjointly with one or another of the main elements to produce by the juncture of their appendage and primary characters a compound accented character. A group of four such auxiliary elements 20 (representing the four principal forms of accents of the Syriac language) is herein shown and described, but it will be understood that a greater or less number may be employed according to the particular 25 language involved.

As before stated, while the present improvements have been designed especially to meet the requirements of the linotype machine, it will be apparent that they are 30 equally applicable to other kinds of machines, such as type setters which employ type or type dies. As a matter of fact, the invention is also applicable to hand-set type and to any other forms of typographical elements 35 which may be manipulated to make up accented characters for printing purposes. In addition, the improvements could be made use of in connection with any language which includes accents, vowels or 40 equivalent signs or symbols. Generally speaking, it is to be understood that the invention is not limited to any specific adaptation or embodiment except in so far as such limitations are specified in the claims.

Having thus described my invention, its construction and mode of operation, what I claim and desire to secure by Letters Patent of the United States is as follows:

1. In a typographical font, the combination 50 of a set of main elements formed with primary characters, and an auxiliary element formed with an appendage character consisting of a primary-character-extension and an accent associated therewith and located wholly within the lateral limits thereof, the said auxiliary element adapted to be used conjointly with one or another of the main elements to produce by the juncture of their appendage and primary characters 55 a compound accented character having its accent located above or below the same in a setwise direction.

2. In a typographical font, the combination 60 of a set of main elements formed with

primary characters, and a group of auxiliary elements each formed with an appendage character consisting of a primary-character-extension and an accent associated therewith and located wholly within the lateral limits thereof, the said accents differing from each other, and the said auxiliary elements being adapted to be used conjointly with the main elements to produce by the juncture of their appendage and primary characters differently accented compound characters having 70 their accents located above or below the same in a setwise direction.

3. In a typographical font for the Syriac or a like language, the combination of a set of main elements formed with primary characters corresponding with the complete unaccented letters of the alphabet of such language, and an auxiliary element formed with an appendage character meaningless in itself and consisting of a primary-character-extension and an accent associated therewith and located wholly within the lateral limits thereof, the said auxiliary element adapted to be used conjointly with any one 80 of the main elements to produce by the juncture of their appendage and primary characters a compound character corresponding to a complete accented letter in true form of the Syriac language.

4. In a typographical font for the Syriac or a like language, the combination of a set of main element formed with primary characters corresponding with the complete unaccented letters of the alphabet of such language, and a group of auxiliary elements 90 each formed with an appendage character meaningless in itself and consisting of a primary-character-extension and an accent associated therewith and located wholly within the lateral limits thereof, the said accents differing from each other, and the said auxiliary elements being adapted to be used conjointly with the main elements to produce by the juncture of their appendage and primary characters compound characters corresponding to complete differently accented letters in true form of the Syriac 95 language.

5. A typographical element formed with an appendage character adapted to be used conjointly with a primary character of another element, the said appendage character consisting of a primary-character extension and an accent associated therewith and located wholly within the lateral limits 100 thereof.

6. A typographical element formed with an appendage character adapted to be used conjointly with a primary character of another element, the said appendage character consisting of a primary-character-extension and an accent associated therewith and located wholly within the lateral limits 105 thereof.

of, the said accent being inclined toward the right for the purpose described.

7. A typographical element formed with an appendage character adapted to be used 5 conjointly with a primary character of another element, the said appendage character consisting of a primary-character-extension

and an accent associated therewith, the said primary-character-extension being formed to connect with the primary character of a 10 succeeding element.

In testimony whereof, I have affixed my signature hereto.

SAMUEL A. JACOBS.
